CLAIM

The ornamental design for a shoe, as shown and described.

DESCRIPTION

FIG. 1 is a front perspective view of a shoe showing my new design;

FIG. 2 is a side view thereof;

FIG. 3 is a rear perspective view thereof; and,

FIG. 4 is a rear view thereof.

The contrast in shading represents a contrast in appearance only and does not represent any particular color, material, texture or finish. The broken lines immediately adjacent to the bottom, front and rear of the shaded areas define the bounds of the claimed design and form no part thereof. The broken lines showing the remainder of the shoe are for environmental purposes only and form no part of the claimed design.
